DESIGN FOR A VENTILATOR

Onnie Mankki, Cleveland Heights, and Francis Joseph Schultheis, Lakewood, Ohio

Application February 14, 1944, Serial No. 112,575

Term of patent 7 years

(Cl. D62—3)

To all whom it may concern:

Be it known that we, Onnie Mankki and Francis Joseph Schultheis, both citizens of the United States and residents of Cleveland Heights and Lakewood, respectively, in the county of Cuyahoga and State of Ohio, have invented a new, original, and ornamental Design for Ventilators, of which the following is a specification, reference being had to the accompanying drawing forming a part thereof.

In the drawing:

incorporating our new design in closed position; and

Figure 2 is a perspective view to a slightly smaller scale of the ventilator of Figure 1 in open position.

The other sides, not shown, are substantially like the side shown.

We claim:

The ornamental design for a ventilator, substantially as shown and described.

ONNIE MANKKI,

FRANCIS JOSEPH SCHULTHEIS.
